UNITED STATES PATENT OFFICE.

BERKELEY B. GARRETT, OF ROANOKE, VIRGINIA.

CALIPERS.

Application filed January 22, 1927. Serial No. 162,843.

This invention relates to a watchmaker's tool, and aims to provide novel means whereby a balance wheel may be trued or straightened, should the same become distorted to affect the operation of the time-piece of which the balance wheel forms a part.

Another object of the invention is to provide a tool of this character having means whereby a watchmaker may determine just where the balance wheel is out of true so that the same may be properly reshaped.

A still further object of the invention is to provide means for securely holding the balance wheel while the same is being bent by the watchmaker, thereby eliminating all possibility of undue strain being brought to bear on the pintle of the balance wheel to bend the same, or render the pintle inoperative.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view of a tool constructed in accordance with the invention.

Figure 2 is an elevational view of one edge of the tool.

Figure 3 is a sectional view taken on line 3-3 of Figure 1.

Figure 4 is a sectional view taken on line 4-4 of Figure 1.

Referring to the drawing in detail, the device includes a body portion indicated generally by the reference character 5, the same being formed of sheet metal and provided with downwardly extended portions 6 defining supporting legs.

One end of the body portion is cut away defining a substantially large opening 7 and a pair of arms 8 and 9 respectively to which arms the members 10 are secured, the members 10 being tubular in formation and provided with internal threads to receive the threaded bearing members 11.

These bearing members 11 are formed with knurled heads 12, whereby they may be moved towards or away from each other

to adjust them for use in supporting a balance wheel, in a manner as shown by Figure 1, the balance wheel being indicated by the reference character 13.

Depressions are formed in the adjacent ends of the bearing members 11 and accommodate the pintle of the balance wheel, to the end that when the bearing members are moved towards each other, they will act to clamp the pintle of the balance wheel to properly support the same.

Pivots supported on the body portion 5 is an arm 14 which is provided with an enlarged portion 15 having an inclined edge 16 to be engaged by the screw 17, which passes through an opening formed in the ear 18. This screw 17 is provided and acts as a stop for the arm 14 to insure against the arm being moved too far when the same is being moved to its active position.

At one end of the wide portion 16 of the arm 14 is a laterally extended flange 19 which is provided with an opening to accommodate the threaded end 20 of the adjustable gauge arm 21, which extends along one edge of the arm 14 and is provided with a right angled extremity 22 designed to engage the balance wheel under treatment, to hold the same while it is being trued.

A threaded opening is formed in the body portion and accommodates the screw 23 formed with a winged portion 24 to permit the same to be readily operated. This screw also passes through an elongated opening 25 formed in the enlarged portion 15 of the arm 14 so that the arm 14 may be adjusted longitudinally of the body portion 5 to accomplish the purpose of the invention.

A clamping member 26 is formed with downwardly extended flanges at its ends, which flanges rest against the edges of the gauge arm and wide portion of the arm 14, to hold the arm 14 and gauge arm in positions of adjustment.

Carried by the arm 14 is a guide member 27 through which the gauge arm 21 moves. Forming a part of the body portion is a bracket 28 disposed in spaced relation with the body portion, the bracket member being designed to support the arm 29 that in turn supports the finger 30 which is pivotally mounted, and which is designed to be moved to a position adjacent to the lower surface of the balance wheel so that the trueness of the balance wheel may be determined readily.

One end of the arm 29 is bifurcated and accommodates the screw 31 which may be operated to clamp the arm 29 and hold the arm in various positions of adjustment.

5 In the operation of the device, a balance wheel which has been distorted and which is to be straightened, is positioned in the bearing members, as clearly shown by Figure 1. The gauge arm and its supporting arm are 10 now moved to a position whereupon the right angled portion 22 of the gauge arm will contact with the inner edge of the balance wheel at the point where the same is out of true.

15 With the balance wheel clamped in this position, the person using the tool may grasp the balance wheel between the thumb and forefinger and by a slight pull, bend the balance wheel to straighten it.

20 I claim:

1. A tool of the class described comprising a body portion having a cut out portion at one end defining a pair of spaced arms, adjustable means carried by the arms for supporting a wheel, means adjustable longitudinally of the body portion for gripping the wheel at its rim, and said gripping means adapted to hold the wheel while it is being straightened.

2. A tool of the class described including 30 a body portion, adjustable means at one end of the body portion for supporting a balance wheel, a wheel gripping member including an arm having a wide portion at one end, means for pivotally supporting the 35 arm on the body portion, an adjustable gauge arm supported adjacent to the first mentioned arm and having a right angled end defining a jaw, said jaw adapted to co-operate with one end of the first mentioned arm to clamp the rim of the wheel to support the wheel while being straightened.

3. A tool of the class described including 40 a body portion, means at one end of the body portion for supporting a balance wheel, an arm pivotally secured to the body portion, a gauge arm mounted for slidable movement on the first mentioned arm, means 45 at one end of the gauge arm for adjusting the gauge arm with respect to the arm supporting the same, said gauge arm adapted to grip a balance wheel at its rim to hold the balance wheel, and means for restricting pivotal movement of the arm.

50 In testimony that I claim the foregoing as my own, I have hereto affixed my signature.

55 BERKELEY B. GARRETT.
